BLAST FURNACE CONSTRUCTION

Arthur J. Boynton, Winnetka, Ill., assignor to
 H. A. Brassert & Company, Chicago, Ill., a corporation of Illinois

Application August 5, 1939, Serial No. 288,503

3 Claims. (Cl. 122—6)

This invention relates to new and improved cooling apparatus for the inwalls of blast furnaces, or for the cooling of other furnaces, where the requirements are similar to those of the blast furnace.

The method of cooling the inwall of the blast furnace has heretofore generally been by means of horizontal rows of coolers placed in the wall of the furnace. These coolers have been made of bronze or of cast iron with steel piping inserted within the casting. They have been located with the faces of the coolers at various distances from the face of the inwall, but usually eighteen inches or more back of the face, and sometimes with the outer edge of the coolers abutting the shell. Location of the coolers with their faces flush with the face of the inwall results in rapid erosion of the inwall into a roughened condition, and is seldom or never practiced. The rows of coolers have been placed at various distances apart in a vertical direction. Each row has generally presented an uninterrupted cooling effect in a horizontal direction. The correct determination of the vertical distance between coolers has depended on the necessity of avoiding the wearing of horizontal grooves in the lining between the horizontal rows of coolers, this wear producing what is sometimes known as a "washboard effect." This condition interrupts the smooth and uniform descent of stock, and is unfavorable to good operation. If the horizontal rows are placed closely together, so as to minimize this "washboard effect," the cost of cooling is increased and the amount of cooling may be so great as to injure the furnace practice. Coolers of the horizontal type have been made removable or irremovable, the removable coolers being supported in part by the shell, either directly or by means of socket plates into which the coolers were inserted. None of these variations in construction have been completely satisfactory.

A variation in inwall cooling has been introduced by the use of cooling plates placed in a vertical position, whereby the grooves formed by wear between the coolers were caused to be vertical. These vertical grooves caused no interruption to the flow of stock, and on this account they were preferable to the horizontal. However, the vertical coolers interposed no limitation on the wear of the wall in the same sense as did the horizontal coolers. The vertical cooling system did not lend itself to incorporation in a system of brickwork laid in courses as well as did the horizontal coolers.

The construction of the present invention overcomes the objections described above as inherent in the use of horizontal or vertical coolers by providing a cooler construction involving both horizontal and vertical cooling members.

It is an object of the present invention to provide new and improved apparatus for cooling the walls of blast furnaces and the like.

It is a further object to provide a cooling system which permits the effective cooling of such furnace walls by means of a substantially permanent installation of low first cost and with a minimum maintenance cost.

It is an additional object to provide a cooling system including both circumferentially and vertically extending members comprising single cooling units.

It is also an object to provide a cooling system located in furnace walls which permits continuous bonding of the brick from a hot area to a cool area.

Other and further objects will appear as the description proceeds.

I have shown a preferred embodiment of my invention in the accompanying drawings, in which—

Figure 1 is a plan view of an individual cooler;

Figure 2 is an elevation of the cooler of Figure 1 as seen from the right;

Figure 3 is a front elevation of the cooler of Figure 1;

Figure 4 is a fragmentary vertical section, partly in diagrammatic form, showing the installation of the coolers in a furnace wall;

Figure 5 is a fragmentary elevation showing a method of connecting to the cooler through the exterior furnace shell of the furnace;

Figure 6 is a fragmentary horizontal section on progressive planes showing the coolers installed in the brickwork of a furnace;

Figure 7 is a vertical section taken on the arcuate line 7—7 of Figure 6; and

Figure 8 is a fragmentary elevation of the outer face of a furnace wall with the coolers installed therein.

The cooler as shown in Figures 1, 2 and 3 comprises four separate extensions. The first extension 11 is adapted to extend horizontally from the inside of the shell to intersect the arc in which the horizontal cooling section 12 of the cooler is to be located. Extension 11, as shown, extends horizontally and radially of the horizontal cross-section of the furnace. This section 11 may be made three inches high and three inches wide to suit the customary thickness of

blast furnace brick as used in this country. This particular dimension is not essential to the invention and obviously the dimensions of all portions of the cooler may be changed to suit the brick with which the cooler is to be used. The arcuate cooling section 12 may be made four and one-half inches wide and three inches thick. It is designed to extend horizontally and at a constant distance from the vertical central axis of the furnace. The length of this extension may be varied to suit the intensity of the cooling effect desired. It may, for usual conditions, be constructed about four feet long.

The substantially vertical extension 13 rises a distance which is the multiple of the thickness of the brick used, less a fraction of an inch for clearance and to guard against any assembling difficulty due to roughness of the casting. This extension is preferably three inches thick in the direction extending circumferentially of the furnace and four and one-half inches wide in the direction radially of the furnace. The number of courses of brick which may be laid above extension 12 in reaching the top of extension 13 will vary in accordance with the intensity of the cooling effect sought. Under usual conditions the height of section 13 may be the equivalent of seven courses of brick.

The horizontally and radially extending fourth extension 14 is similar in dimensions to the first inwardly extending section 11. Extension 14 connects the vertical cooling section 13 and the shell of the furnace.

In Figure 4 the brick lining or wall of the furnace 15 is supported on a foundation 16 and enclosed in a metallic shell 17. This figure shows the portions 12 and 13 of the cooler as seen in horizontal section and in vertical elevation.

In Figure 6 is shown the relationship of the cooler to the brickwork, this section making clear how the various layers of brick below, above and on the plane of the horizontal section 12 of the coolers may be installed to insure a proper continuous bond of the brickwork in both the vertical and horizontal directions.

In Figure 7 is shown one method of installing the coolers in the brickwork with the horizontal cooling sections 12 in adjacent coolers located to form continuous cooling rings circumferentially about the furnace while the vertically extending cooler sections 13 are staggered in alternate rows to provide maximum resistance to wear in a horizontal direction. It will be understood that if desired the coolers may be located with the vertical sections 13 of the coolers in successive series in alignment to provide continuous cooling surfaces in both directions. Similarly, if desired, the horizontal sections 12 of the coolers may be placed in the furnace in a manner to afford staggered or offset cooling sections in this direction.

It will be understood that the coolers are connected to pipes for introducing and withdrawing cooling water. One method of making such a connection is shown in detail in Figure 5 where the shell 17 of the furnace is provided with a rectangular opening 18. The rectangular plate 19, indicated in broken lines, is located within the shell behind the opening so as to afford a full closure of the opening upon settling or movement of the brickwork relative to the shell. The radial section 11 of the cooler has a water pipe 20 connected thereto. A general method of connecting up a plurality of coolers is shown in Figure 8 where the pipes 20 are shown as connecting one

cooler section 14 to the section 11 of an adjacent cooler.

It will be apparent that effective cooling is done by the faces of extensions 12 and 13 which are nearest the face of the inwall, and that this cooling extends in both a horizontal and vertical direction. The result is that erosion of the wall by softening of the brick, and subsequent abrasion of the descending stock, is limited in a vertical direction by the horizontal extension 12 and in a horizontal direction by the vertical extension 13.

It will also be apparent that the cooler is firmly held in position by the bedding of extensions 11, 12 and 14, by the connection of extensions 11 and 14 at the shell, and by the bonding of all four extensions into the brickwork of the furnace.

It will be apparent that a continuous bonding of the brick from the face of the inwall to the shell is possible, in spite of the presence of the cooler, and that the cooler interferes very little with such bonding. It is consequently impossible for the brick to drop out of the wall, as is the case where L plates are used and the bond of the brick thereby substantially destroyed, or as is the case where the lining becomes thin next the shell. In the case of brickwork laid in conjunction with the cooler of the present invention the brick is continuously bonded from a hot area into a cool one, and destruction of the wall by the bodily dropping out of bricks is prevented.

The system of cooling, according to this invention, consists in placing individual coolers in the wall in such relationship to each other that wear will be minimized. This will generally result in placing the individual coolers so that continuous horizontal lines of cooling will be formed by the second extensions of the respective coolers, while staggered placing of the third extensions of alternate horizontal rows of coolers will provide maximum resistance to wear in a horizontal direction. It will also be possible to provide continuous cooling surfaces in both directions.

It will be apparent that the extent of cooling at various heights of the furnace may be varied by changing the shape and position of the individual coolers, so as to bring the cooling closer to the face of the inwall, and also so as to increase or decrease the vertical and horizontal distance between cooling faces. It is also possible to build extension 13 vertical, or slightly inclined to suit the nominal batter of the inwall.

While I have shown one preferred embodiment of my invention, this is to be understood to be illustrative only as it is capable of variation to meet differing conditions and requirements and I contemplate such modifications as come within the spirit and scope of the appended claims.

I claim:

1. A cooler for furnace walls comprising an elongated hollow member of substantially uniform cross-sectional area throughout its length and having a portion adapted to extend inwardly from the outer face of a furnace wall, a second portion at approximately right angles to the first section and adapted to extend horizontally approximately parallel to the face of the wall, a third portion adapted to extend vertically of the furnace wall, and a fourth section adapted to extend from the third portion to the outer face of the furnace wall.

2. A cooling system for furnace walls consisting of brickwork comprising a plurality of coolers each having a horizontally extending cooling portion and a directly connected vertically ex-

tending cooling portion, said coolers being placed in the brickwork of the walls to provide practically continuous horizontal cooling faces connected at intervals by vertically extending cooling faces.

3. A cooling system for furnace walls comprising a plurality of coolers each having a horizontally extending cooling portion and a directly connected vertically extending cooling portion, said coolers being placed in the walls to provide 10

practically continuous horizontal cooling faces connected at intervals by vertically extending cooling faces, the coolers being of a cross-sectional area slightly smaller than the brick used in the wall and of substantially the same cross-sectional form as the brick, and being so related to the brick area that the brickwork of the wall is continuously bonded from hot side to cool side.

ARTHUR J. BOYNTON.
